UNITED STATES PATENT OFFICE.

RICHARD K. MEADE, OF BALTIMORE, MARYLAND.

KILN.

1,416,657.

Specification of Letters Patent. Patented May 16, 1922.

Application filed June 23, 1921. Serial No. 479,732.

To all whom it may concern:

Be it known that I, RICHARD K. MEADE, a citizen of the United States of America, residing in the city of Baltimore, State of Maryland, have invented certain new and useful Improvements in Kilns, of which the following is a specification.

The invention relates to improvements in lime and similar kilns. The kilns to which my invention has particular application are the cupola or vertical type comprising an upright stack or cupola to which the stone to be burned is fed at the top, the heat being supplied from one or more furnaces at the bottom. In order to produce a uniform product and achieve economical operation of the kiln it is necessary to maintain a considerable degree of uniformity of operation and to this end it is necessary to maintain a uniform supply and distribution of air. The air is fed by natural draft or suction established in and through the apparatus when the materials and furnace are heated and the quantity of air passed through the apparatus is determined by the air opening at the bottom.

The coal consumption and grate areas employed in this connection are small and it has been customary to feed the furnaces which ordinarily burn coal by hand but the necessity for opening the furnace doors during stoking and feeding has, on account of the high degree of suction developed, resulted in the influx of an excess of air when the furnace is opened. The excess of air thus admitted is detrimental as excess cooling due to the heat abstracted from the ore or stone by contact with the air which cannot be consumed and therefore merely passes through the kiln acting as a heat carrier or heat vehicle. The cooling of the furnace which results in this way effects a corresponding cessation of the operation of the kiln for the rock can only be burned at certain definite temperatures. To counteract such influxes of cold air it would be necessary to maintain a much higher normal furnace temperature than that which is necessary when the operation can be made uniform form.

It is to the accomplishment of such uniformity of operation and air distribution that the most important feature of the present invention is directed. As already pointed out the most common cause of the excess air supply is the necessity for opening the

furnaces during feeding and stoking and as further pointed out the fuel consumption of such apparatus is too small to make an automatic stoker effective or desirable, in fact the expense in accordance with the present practice and conditions is considered prohibitive.

To overcome the difficulties stated I have provided in connection with a vertical or cupola type of lime or similar kiln, a hand operated stoker which is completely closed and arranged that the fire can be efficiently maintained for an indefinite period under all conditions without the necessity for opening the furnace to give access thereto for stoking purposes. The stoker or furnace being also provided with a hopper feed which is completely closed under all normal furnace conditions which makes it possible to regulate the air supply to give uniformity of feed and distribution and hence regularity and uniformity of operation, it being understood that the operation of the kiln is continuous, the ore or stone being fed in at the top and the burned or finished material removed from the bottom without pause as to or interference with the burning operation.

The invention further relates to the bottom portion of the furnace, i.e., to an improved type of cooling cone adapted to hold and cool the material when it reaches the bottom of the furnace after burning just prior to its release and to an improved releasing means or shears and the details thereof.

In the accompanying drawings I have illustrated a kiln structure embodying the various features of my invention in the preferred form.

Figure 1 is an elevation partly in section showing the entire kiln structure on a small scale;

Figure 2 is a section on the line 2—2 of Figure 1, same being comparatively enlarged;

Figure 3 is an enlarged section on a vertical plane taken longitudinally of the furnace and stoker;

Figure 4 is a horizontal section on the line 4—4 in Figure 5;

Figure 5 is an elevation of the shears showing the foundation walls in section.

Referring to the drawings by numerals the structure as shown comprises a kiln including an upright or vertical portion or

kiln proper 1, furnaces 2, by which the kiln is heated, cooling cone 3 and foundation or base 4.

The kiln proper as shown consists of a 5 cylindrical jacket or shell 5 which in the form illustrated is built up of boiler plates or similar material enclosing an upright masonry structure 6 which may be lined with fire brick and tapered to give a diminishing cross section toward the bottom. 10 The tapering chamber thus formed is in the operation of the kiln filled with the lime stone 7 to be burned, which lime stone may be supplied by means of a tramway 8, terminating on a platform 9, at the top of the kiln from which the material is dumped into the kiln.

The furnace structure 2, by means of which the heat for treating or burning the limestone is supplied is best illustrated in 20 Figure 3. The desired change in the material is accomplished by heating the limestone to a sufficient temperature driving off moisture and carbon dioxide and leaving calcium oxide known as lime or quick lime. The heat is communicated to the stone in the kiln by means of the products of combustion which are passed through the kiln which in this connection acts as a chimney or stack 25 for the furnace. The gradual heating of the materials in the kiln serves to set up a sufficient natural draft.

It has been customary in the past to feed and stoke the furnaces, which are comparatively small, by hand but it is found that the opening of the furnace doors incidental to hand feeding and stoking results in the introduction of an excess of cold air which is drawn through the kiln accomplishing no 30 useful result and abstracting a considerable amount of heat. Actual tests show a reduction of efficiency evidenced by a less amount of CO_2 given off when the furnace doors are open and the cooling and subsequent 35 irregularity of operation are harmful in various ways effecting the economy, efficiency and the quality in the way of uniformity of the product.

To overcome these difficulties in the operation of coal burning kiln, I have provided a 40 hand operated automatic feeding and stoking device which is complete in itself and capable of operation for long periods, in fact indefinitely, without opening the furnace 45 doors so that the air supply to the furnaces and kilns may be regulated in exact accordance with the chemical requirements of the process including the combustion of the fuel 50 eliminating the necessity for admitting excess air with the consequent loss of efficiency and uniformity of operation and of distribution as already pointed out.

To this end each of the furnaces 2, is provided with a hand stoking apparatus 55 consisting of a grate 11, made up of arcuate

grate sections 12, mounted to swing on journals 13, and connected together in alternately arranged series by links 15' to be operated from outside the furnace by means of rods 15 so that by rocking the series of 70 grate sections alternately, the fuel may be fed along the grate which is inclined for this purpose and the burned material may be dumped at the end by means of the dumping section 14 which is likewise operated 75 from outside the furnace by means of a rod 16 extending through the front wall of the furnace. The fuel opening of the furnace is closed by means of a hopper 17 from which the fuel may be fed as needed or more 80 or less automatically fed and distributed by the stoking operation. The important feature is as already pointed out that the fire is fed and maintained without the necessity for opening the furnace doors during the 85 operation of the kiln. The stoking grate referred to is fully described in the Huber Patent No. 1,232,687.

In Figures 4 and 5 and to some extent in Figure 1, I have illustrated the details of 90 the cooling cone and shears, the cooling cone being the structure illustrated by reference character 3, consisting of an inverted frustum of a cone made of sheet iron and supported beneath the kiln to receive and hold 95 the burned lime, cooling it prior to delivery from the furnace to the barrel. The cooling cone may to advantage be provided with a water jacket 18, which prevents burning of the cone structure and assists the cooling of 100 the lime. The jacket is supplied with water by way of a pipe 19 from any suitable source and the water may be released by way of an outlet 20, which may be controlled by any suitable valve 21. The bottom of the cone 105 22, through which the material is discharged is controlled by suitable doors known in the lime burning art as shears.

The present invention includes an improved shear structure illustrated particularly in Figures 4 and 5. This consists of two rectangular plates 23, each of which is suspended by suitable stirrups 24, each said stirrup engaging opposite corners at one end of a plate so that there is one stirrup at each end of each plate. These four stirrups extend upward from the plates and are pivoted at their upper ends to horizontal transverse supports 34, controlled by means of links or connecting rods 25. These rods 110 are pivoted to the shear plates by pins 26, each near an outside corner of the plates, it being understood that there are four of these rods, and that each is pivoted at its opposite or swinging end to an arm 27 which 115 is secured to and swings with shaft 28, each said shaft 28 being provided with two arms 27, which are spaced apart and pivotally connected to the free or swinging ends of 120 corresponding connecting rods 25. 125

The shafts 28 of which there is one on each side of the shears are provided each in addition to the arms 27, with an actuating arm or lever 30, which controls the rocking of the 5 corresponding shaft 28 and the opening and closing of the shears. The arms 30 project on the same side of the shafts 28 as do the arms 27, that is, toward the outside and away from the cone, the shears being placed 10 on the opposite or inside of the shaft and the parts are so arranged that the actuating arm of each shaft approaches the vertical depending position when the shears are closed so that the weight of the arm tending 15 to swing the shaft downward causing the lower side of the shaft to swing toward the cone, tends to maintain the shears closed giving a gravity closing action of the shears. Also the manner of the suspension of the 20 shear plates as illustrated is such as to cause them to be suspended directly from and beneath the pivots submitting the supporting means to a direct stress which is substantially of tension only and eliminating all 25 harmful transverse stresses. The lever arms 27 about the shafts 28 are very much shorter than the stirrups and the hand levers 30 are longer than either, giving powerful leverage in controlling and actuating the 30 shears.

I have thus described specifically and in detail a single structure embodying my invention in the preferred form in order that the nature and operation of the same may 35 be clearly understood. However, the specific terms herein are used descriptively rather

than in a limiting sense, the scope of the invention being defined in the claims.

What I claim and desire to secure by Letters Patent is:

1. In a kiln for burning lime or the like the combination of an upright ore chamber, a coal burning furnace at the bottom of the chamber connected to the ore chamber so the latter acts as a stack, a stoking grate in the 40 furnace composed of rocking sections and a drop bar means for operating the stoking grate from outside the furnace, hopper feeding means for supplying the fuel to the grate the bottom of the kiln and the furnace being closed normally and during stoking to prevent the admission of excess air to the kiln.

2. In a lime kiln the combination of an upright kiln chamber, a furnace at the bottom of the chamber connected to the ore chamber so that the latter acts as a stack for the furnace, a stoking grate with means for dumping the unburned residue and manually actuated means for operating the same 55 from outside the furnace, a hopper for feeding fuel to the grate the bottom of the kiln and the furnace being closed normally and during stoking to prevent the admission of excess air to the kiln.

Signed by me at Baltimore, Maryland, this 17th day of June, 1921.

RICHARD K. MEADE.
